[57] CLAIM

The ornamental design for a seat, as shown and described.

DESCRIPTION

FIG. 1 is a left front perspective view of a seat showing my new design;

FIG. 2 is a side elevational view thereof; the opposite side elevational view being a mirror image thereof;

FIG. 3 is a front perspective view thereof; and,

FIG. 4 is a rear perspective view thereof; and,

FIG. 5 is a right rear perspective view thereof; and,

FIG. 6 is a top elevational view thereof.

The bottom elevation view of the design is not shown and forms no part of the claimed design.
